Charles E. Dodd ^{Inventor}
By Truman E. Hodges
Truman E. Hodges ^{Attorney}

UNITED STATES PATENT OFFICE.

CHARLES E. DODD, OF WILLIAMSPORT, PENNSYLVANIA.

FASTENER.

Application filed March 6, 1925. Serial No. 13,468.

My invention relates to an improvement in fasteners.

This improved fastener may be used for various purposes; for example in one form as a paper-fastener; in another, as a box lid support; and in still another form as a hanger. In fact it might be employed in a still greater variety of uses, as it consists of a spring clip of peculiar construction which insures a rigid hold upon the material or article pinched between the spring-jaws composing the main portion of it.

In the accompanying drawings:

Fig. 1 is a view in perspective showing it applied to a paper box of one design;

Fig. 2 is an end view;

Fig. 3 is a side view with a portion broken away at the center to allow for enlargement;

Fig. 4 is a view of a hanger;

Fig. 5 is a perspective showing the device applied to a slightly different form of box-lid from that shown in Fig. 1.

Referring to Figs. 1, 3 and 5, the numeral 25 1 illustrates the center of the wire forming the box-lid support, 2 being the body of the box, and 3 the lid. This lid, in the form shown in Fig. 1, has a flange 4, there being none in the box-lid shown in Fig. 5. In the 30 form of device shown in Figs. 1 and 3, the device terminates at each end in an acute angle, as viewed in Fig. 3, to accommodate the relative position of the box and box-lid. The clip portion itself is formed by bending 35 the wire into two spring jaws or members 5 and 6, as shown in detail in Fig. 2. The member 6 is bowed or curved inwardly, and the main portion of the member 5 is straight. This constitutes the most essential feature 40 of the present invention.

The convex curvature 7 forming a gripping surface of sufficient area always to take a rigid hold upon any object sprung between the two spring members or jaws, takes 45 care of the varying thicknesses without appreciably changing the amount of gripping area, for while the straight portion 6 remains more or less constant in its gripping action, the active gripping area of the curved 50 surface 7 may change slightly throughout its length according to the thickness of the

object pinched or gripped between the two members or jaws.

The eye 8 gives both the required resiliency and rigidity, and sufficient length of 55 area to permit of the go and come of the jaws, and to provide a constant pressure upon the object held between them.

The convergence at the open end forms a 60 guide for the entrance of the object held. With a device of this character, the object to be held is firmly and securely fastened, and the spreading of the jaws with the gripping 65 of the object does not lessen the area of gripping surface, in which respect this device differs radically from one in which there is no curvature such as illustrated at 7 in the spring jaw or member 6.

In Figures 1 and 5, the gripping device 70 is disposed to suit the requirements of the two different forms of boxes and box-lids. In Fig. 4, the center 9 is bent into a V-shape, and an eye 10 is formed to constitute a convenient form of hanger.

This constitutes a simple, inexpensive, and 75 efficient fastening means for a variety of purposes, not only those illustrated and described, but an infinite variety of other uses.

I claim:

1. A box lid holder comprising clasps, 80 each of said clasps having side members forming clamping jaws joined together at their outer ends, and open at their inner ends to receive a portion of an article to be fastened therein, the open end of each of the 85 clasps being joined to the open end of the other clasp, the open mouths of said clasps being arranged approximately in the same plane.

2. A box lid holder of the character described comprising clasps, each of said clasps having two substantially straight side members joined together at their outer ends, and separated at their inner ends to form a 95 mouth for the reception of an article to be fastened therein, and a straight connecting portion extending in a straight line from the inner end of a side member of one of the clasps to the inner end of a side member of the other clasp.

In testimony whereof I affix my signature.

CHARLES E. DODD.
